UNITED STATES PATENT OFFICE.

ALFRED BREEHL, OF LOUISVILLE, KENTUCKY.

TRUNK.

1,165,063.

Specification of Letters Patent. Patented Dec. 21, 1915.

Application filed February 15, 1915. Serial No. 8,148.

To all whom it may concern:

Be it known that I, ALFRED BREEHL, a citizen of the United States, residing in the city of Louisville, county of Jefferson, and 5 State of Kentucky, have invented a certain new and useful Improvement in Trunks, of which the following is a specification.

This invention relates to improvement in "trunks", or analogous receptacles, in 10 which the front wall of the body of the trunk is of less height than the rear wall, the end walls sloping from the rear forward, and in which the lid fits upon, or overlaps, the upper margin of the body.

15 An object is to provide an overlid trunk, or case, having characteristics mentioned above which shall be simple, strong, and rigid in construction.

20 A further object is the provision of a trunk, the lid of which may be raised, to a vertical position, when the back of the trunk is against the wall, which is usually the case, without the necessity of moving it from the wall, and in which the lid will remain in an 25 open position without the use of braces.

With the foregoing and other objects in view the invention consists of the novel arrangement and construction of parts illustrated in the accompanying drawing which 30 forms a part of this specification, wherein is set forth an embodiment of the invention, but it is to be understood that such changes and modifications may be resorted to as come within the scope of the appended claims.

35 Referring to the drawing wherein similar reference characters designate like parts in the several views; Figure 1, is an end elevation of an embodiment of my invention, with the lid closed, one corner being broken 40 away to show the construction; Fig. 2, a view similar to Fig. 1, with the lid raised; Fig. 3, a side elevation of the hinge employed; Fig. 4, a top plan of the hinge; Figs. 5, and 6, plan and end elevations, respectively showing how the leaves of the hinges 45 are assembled.

Referring now more particularly to the drawing, the numeral —1— designates the body of the trunk and —2— the lid there- 50 for. A hinge strip —3— secured to the rear side wall —4— extends forward and upward therefrom at a suitable angle, preferably about 35 degrees from the horizontal. From the forward edge of this hinge strip the upper edge of the ends of the body slope forward and downward at a slight angle from

the horizontal. A hinge strip —5— secured on the rear of the lid 2, projects downward and rearward from the top panel —6— to a meeting point with the hinge strip 3, the 60 two strips lying in the same, or parallel, planes. The upper surface of the lid lies in a horizontal plane the lower edge of the ends complementing the ends of the body, the inclination of the juncture of the ends 65 of the body and the lid being just sufficient to provide a vertical lock strip on the front of the lid, the arrangement being such that the mass of the lid lies above a horizontal line drawn through the meeting points of 70 the hinge strips so that when the lid is raised the center of gravity will fall in the rear of the hinge point and the lid will not require any support to hold it open nor will it pass the vertical plane of the rear wall of 75 the body. Consequently it will not be necessary to move the trunk from against the wall, where it may be standing, in order to open it. The lid is connected to the body of the trunk by a plurality of hinges such 80 as —7— which are suitably secured to the hinge strips. The hinges each comprise two leaves —8 and 9— each of which is bent at a suitable point in its length to conform respectively to the top and back of the trunk 85 and to the strips 3 and 5. The leaf 8 comprises a body portion —10— and a depend- 90 ing portion —11—. On the body portion is an elevation or abutment —12— the forward face —13— of which slants backward at an 90 angle of approximately 10 degrees from a line vertical to the plane of said body por- 95 tion. A plurality of members —14— extend forward from the face 13, curving down- 100 ward and rearward to within a spaced dis- tance of the body 10, leaving a space —24— therebetween. The leaf 9 comprises a body portion —15— and an extended portion —16—. The body portion is provided with a plurality of openings —17— adapted to receive the members 14, the portion —18— lying within said member and serving as the pintle on which the hinge turns. The thickness of the body 15 is greater than the width of the space 24, consequently in order 105 to introduce the member 14 into the spaces 17 a groove —19— is provided, in the face of the body, leading to said spaces whereby, by holding the leaf 9 at an angle to leaf 8 as shown in Fig. 6, it may be slid along 110 (see Fig. 5) until the hooks 14 enter the spaces 17, when the leaf may be raised to

its operative position, in which position the leaves are inseparable. It will be observed that with the hinge in its operative position (see Fig. 3) when the leaf 9 is raised so that 5 the plane of the portion 16 is vertical the portion 15 rests against the abutment 12 which holds in that position; in this position the center of gravity of the trunk lid falls in the rear of the pintles of the hinges 10 and consequently the lid will not fall forward.

Having thus described my invention so that anyone skilled in the art pertaining thereto, may make and use the same I claim:

15 1. In a trunk, a body, a lid therefor, a hinge strip arranged along the upper edge of the rear wall of said body and extended forward and upward at an obtuse angle to said wall, a complementary strip depending 20 from said lid and lying in the same plane as, and abutting against said first named strip, the juncture of the ends of the lid and body lying in a plane extended forward from the juncture of said strips and at an 25 acute angle from a horizontal line drawn through the juncture of said strip, whereby the mass of the lid lies above such horizontal line.

2. In a trunk, a body, a lid therefor, a hinge strip arranged along the upper edge of one wall of the body and extended at an obtuse angle therefrom, a complementary strip depending from said lid lying in a plane parallel with and abutting against 35 said first named strip, a plurality of hinges

mounted on said strips and joining said body and lid, each of said hinges comprising a pair of leaves, an abutment extended vertically from one of said leaves, a plurality of recurved members extended from the 40 face of said abutment, the other of said leaves having a plurality of slots spaced from the butt end thereof and adapted to receive said recurved members.

3. In a trunk, a body, a lid therefor, a hinge strip arranged along the upper edge of one wall of said body and extended upward at an obtuse angle therefrom, a complementary strip depending from said lid lying in a plane parallel with and abutting 45 against said first named strip, a plurality of hinges mounted on said strips and joining said body and lid, each of said hinges comprising a pair of leaves, a block erected on one of said leaves at the butt end thereof, a 50 plurality of recurved members extended from the center of the face of said block and terminating a spaced distance from and in the plane of said leaf, the other of said leaves having a plurality of slots adapted to 55 receive said members, the thickness of said leaf being greater than the width of said space, said leaf having a groove leading from one edge thereof to said spaces whereby said recurved members may be introduced into said slots.

ALFRED BREEHL.
